[57] CLAIM

The ornamental design for a sink, as shown and described.

DESCRIPTION

FIG. 1 is a right side elevational view thereof, the left side being a mirror image of the right side;

FIG. 2 is a top plan view thereof;

FIG. 3 is a front elevational view thereof;

FIG. 4 is a right side elevational view thereof, the left side elevational view being the mirror image of the right side shown;

FIG. 5 is a bottom plan view thereof;

FIG. 6 is a rear elevational view thereof;

FIG. 7 is a cross-sectional view taken on line 7—7 of FIG. 2;

FIG. 8 is a cross-sectional view taken on line 8—8 of FIG. 2;

FIG. 9 is a perspective view taken from the top front and left-side of a second embodiment thereof, the front and sides thereof being the same as FIGS. 3 and 4, respectively;

FIG. 10 is a top plan view of FIG. 9;

FIG. 11 is a bottom plan view of FIG. 9;

FIG. 12 is a rear elevational view of FIG. 9; and,

FIG. 13 is a cross-sectional view taken on line 13—13 of FIG. 10. The fragmentary broken line representations of fixture mounting holes in FIGS. 1, 2, 5, 9, 10 and 11 are for the purpose of illustration only and form no part of the claimed design.

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

UNITED STATES PATENT AND TRADEMARK OFFICE
CERTIFICATE OF CORRECTION

PATENT NO. : Des. 353,652
DATED : December 20, 1994
INVENTOR(S) : Todd D. Dannenberg

It is certified that error appears in the above-identified patent and that said Letters Patent is hereby corrected as shown below:

Title page, col. 2,

The description of Fig. 1 should be as follows:

--Fig. 1 is a perspective view taken from the top, front and left side of a sink embodying my new design;--

The description of Fig. 4 should be the following:

--Fig. 4 is a right side elevational view thereof, the left side being a mirror image of the right side;--

Signed and Sealed this
Seventh Day of March, 1995
